1. This invention relates to improvements in continuous flow kilns and particularly those adapted for drying lumber.

An object of this invention is to provide a kiln for more effectively and efficiently seasoning lumber or other substances.

Another object of this invention is to provide a device of the character described which will dry material evenly throughout no matter where the said material is placed in the work receiving area thereof.

A further object of this invention is to provide a kiln with means for reversing the flow of the drying air when desired.

Another object of this invention is to provide a device capable of converting an old style kiln to a modern cross circulation kiln with a minimum amount of expense.

A still further object of this invention is to provide a device as described requiring only a single air impeller.

A still further object of this invention resides in the particular efficient arrangement of air ducts employed in the device.

Another object of this invention is the provision of a simplified device of the character described which obviates the necessity of utilizing a plurality of air impellers and obviating extensive and costly air ducts.

Other objects and features of novelty of this invention will be specifically pointed out or will become apparent when referring, for better understanding of this invention, to the following description taken in conjunction with the accompanying drawings wherein:

Figure 1 is a side view of the invention shown partly in elevation and partly in section;

Figure 2 is a longitudinal sectional view taken substantially on the line 2-2 of Figure 1 with portions of the heating tubes not shown for clarity;

Figure 3 is a front sectional view of the invention with certain portions shown in section and others in elevation;

Figure 4 is a sectional detail taken substantially on the line 4-4 of Figure 3 showing the fan and certain associated ducts used in the instant invention, and

Figure 5 is a fragmentary longitudinal section taken on line 5-5 in the direction of the arrows of Figure 2 showing the apertures in one of the ducts which are adapted to be used as inlets and outlets.

Referring now to the drawings more in detail for a complete understanding of the illustrated

UNITED STATES PATENT OFFICE

2,505,414

CROSS CIRCULATION KILN

Lawson H. Love, Waskom, Tex.

Application November 20, 1946, Serial No. 711,161

3 Claims. (Cl. 34—191)

1

This invention relates to improvements in continuous flow kilns and particularly those adapted for drying lumber.

2 preferred embodiment of the instant invention and wherein like reference characters are used to indicate similar parts throughout the views of the device; the reference numeral 10 is used to 5 designate the invention in general terms.

A kiln structure 12 which may be made of any 10 usual design or configuration and which may be made of any approved or conventional material is provided having dimensions commensurate 15 with the type of work for which it is to be employed.

The interior of the kiln 12 is provided with the 20 usual ties 14 supported by conventional posts 16. Rails 18 adapted to receive trucks or cars 25 20 are provided on the ties 14. It is here noted that a partition in the form of a vertical bank of longitudinally extending heating tubes substantially divide the kiln working area into two 30 chambers. This vertical bank of tubes, indicated 20 at 22, is of conventional design having each tube in spaced relation to each other permitting air to flow therethrough freely. As is quite apparent from an inspection of Figure 3 the said tubes are secured to suitable vertical studs 24 which extend from the table member 14 to the ceiling of the kiln. Beneath the said bank of tubes is a longitudinally extending baffle 26 which extends substantially the full length of the working area in the said kiln.

35 Referring now to the improved system of ducts used in conjunction with the instant invention, reference to Figure 2 is now made. A fan or impeller 28 is shown having an outlet duct 30 secured to the impeller housing by some suitable means such as soldering or the like and a second 40 inlet duct 32 is suitably secured to the impeller housing 28. Said duct 30 is curved to suitably and substantially follow the wall contour of one side of the device and a second duct 34 of substantially the same configuration as the above 45 described duct 30, is provided following generally the contour of the opposite longitudinal wall, which wall is opposite to the one followed by the said duct 30. It is noted that the end portion of duct 34 is joined to the duct 30 for purposes to be described hereinafter. A final duct 36 extending transversely of the kiln and having junctions with the above mentioned ducts, 30, 32 and 34. At spaced intervals along the length of the ducts 50 30 and 34 is provided a plurality of apertures receiving upwardly extending cylinders 38 for receiving or discharging air as shall be described hereinafter. It is noted also that the ducts 30 and 34 are tapered reducing in cross section as 55 they approach their respective closed ends 40

and 42. Obviously, the rate of flow characteristic through each cylinder 38 is rendered constant throughout.

The operation of the flow producing device and its associated air ducts shall now be described in detail. Extending from the impeller 28 is a shaft 44 adapted to be driven by some suitable power unit such as a dynamo, turbine or the like, and secured to the said shaft 44 is a flow producing means shown as an air impeller 46 for convenience. As shown the duct 30 is secured to the outlet side of the air impeller housing, the second duct 34 is connected to the duct 30 at junctions 48 wherein a manually operated gate valve 50 is provided for selectively opening the duct 34 and thereby closing the duct 30 or on the other hand opening the duct 30 and closing the duct 34. Adjacent the said junction 48 is a second junction 52 formed by the connection of duct 36 to duct 30. The opposite end of said duct 36 is suitably joined to duct 34 as shown clearly in Figure 2. At substantially longitudinal central point of the said duct 36 is a junction 54 made by the connection of the herein before mentioned duct 32 and provided at this junction is a gate valve 56 adapted to close either half of the said duct 36 and thereby opening the other half thereof. By proper manipulation of the valves 50 and 56 the flow of air through the said ducts can be reversed. When the said valves are in the positions as shown in Figure 2 it will be noted that air discharges through a small portion of the duct 30 and strikes the valve 50 which diverts it through the duct 34 whereby it is discharged through the cylinders 38 and into the kiln. Further, with the valves in the positions as shown, the intake side of the impeller sucks air through the open half of the duct 36 which receives the same through the cylinder 38 and the greater portion of the duct 30. When the valves are moved to their alternate positions, it is quite evident now that the duct 34 will draw in air and the duct 30 will discharge the same thereby reversing the air flow in the kiln.

Following now the flow pattern shown in Figure 3 it will be seen that air discharging from the impeller 28 through the cylinders 38 rises, already being heated to a certain degree by proximity to the conventionally disposed heating tubes 58, to a position adjacent the specially provided swinging valve or baffle 60 thence whirls around and through the material to be dried. As is evident from the drawings the air flows through a first compartment, regains some of its lost heat by circulating around the specially provided and herein before discussed banks of tubes 22 thence through the material to be dried in the second compartment traveling then to a low pressure area created by the section communicated by the cylinders 38 in the duct 34. It will be noted that the baffle 60 herein before mentioned guides the lower portion of the air through the transverse bank of tubes 22. The slot valves 60 or baffles are as disclosed in order that they may be efficiently operable when the drying air is flowing in either direction.

The operation and structure of the single embodiment of the inventive concept is hereinabove fully set forth in detail. However, while there is

illustrated but a preferred embodiment of the said invention, it will become apparent to those skilled in the art that various changes, including additions and omissions, may be made herein without departing from the spirit and scope of this invention as set forth in the accompanying claims.

Having thus described the instant invention, what is claimed as novel and improved is as follows:

1. A continuous flow kiln for drying lumber comprising a housing having walls and a ceiling, heating means in said housing, an air impeller having a casing in said housing, an air inlet and an air outlet in said casing, a first apertured duct secured to the casing and communicated with the outlet, a second apertured duct having a junction with the first duct, a valve in said junction for selectively closing said first and second apertured ducts from communication with said outlet, a transverse duct interconnecting said apertured ducts, and an air conduit secured in said casing inlet and secured to said transverse duct.
2. A continuous flow kiln for drying lumber comprising a housing having walls and a ceiling, heating means in said housing, an air impeller having a casing in said housing, an air inlet and an air outlet in said casing, a first apertured duct secured to the casing and communicated with the outlet, a second apertured duct having a junction with the first duct, a single valve in said junction for selectively closing said first and second apertured ducts from communication with said outlet, a transverse duct interconnecting said apertured ducts, a conduit secured in said casing inlet and secured to said transverse duct intermediate its ends, and means in said transverse duct at its junction with said conduit for selectively directing air flow to said inlet from said first and said second apertured ducts.
3. The combination of claim 2 and spaced baffles swingingly suspended from said housing ceiling, a platform in the housing above said first and second apertured ducts, heating tubes below said platform, heating tubes forming a vertical partition rising from said platform, and one baffle disposed on each side of said vertical partition.
